UNITED STATES PATENT OFFICE.

WILLIAM N. HOUGHTALING, OF ANSONIA, CONNECTICUT.

YIELDING HORSE-COLLAR SUPPORTER.

SPECIFICATION forming part of Letters Patent No. 651,188, dated June 5, 1900.

Application filed November 27, 1899. Serial No. 738,249. (No model.)

To all whom it may concern:

Be it known that I, WILLIAM N. HOUGHTALING, of Ansonia, in the county of New Haven and State of Connecticut, have invented 5
5 a new Improvement in Yielding Horse-Collar Supporters; and I do hereby declare the following, when taken in connection with the accompanying drawings and the letters of reference marked thereon, to be a full, clear, 10 and exact description of the same, and which said drawings constitute part of this specification, and represent, in—

Figure 1, a view, partly in side elevation and partly in vertical section, showing my 15 improved horse-collar supporter; Fig. 2, a view in front elevation, showing the attachment of the forward end of the supporter to a horse-collar; Fig. 3, a detached view of the bracket in which the rear end of the supporter is swiveled.

My invention relates to an improvement in the horse-collar supporter patented to me July 11, 1899, No. 687,391, the object being to produce a simple, cheap, and effective device 25 for lifting a hame-collar above the neck of a horse, so as to avoid chafing.

With this end in view my invention consists in certain details of construction and combinations of parts, as will be hereinafter 30 described, and pointed out in the claims.

In carrying out my invention I employ a collar-supporter made from a long rod of elastic metal and made straight at its rear end to form a vertical pivot A, which merges 35 into an arch-shaped chain-fender B, which in turn merges into a long forwardly-extending reach C, terminating at its forward end in a loop D, the end of which is bent downward and rearward and ends in a hook E, which 40 latter is designed to be hooked directly under the strap F, uniting the bowed upper ends of the hames G G at a point above the apex of the hame-collar H, as shown in Fig. 2. The pivot A of the device is set into a socket I, 45 formed in a bracket I', secured by bolts or screws J J to the rear face of the chain-bow K of the saddle, which may be of any approved construction. The said chain-bow is formed in the usual manner with a channel 50 K', receiving a chain L, which is prevented from jumping forward out of the channel by

means of the chain-guard B, the forward end of which is bent downward, so as to just clear the forward edge of the chain-bow, as shown in Fig. 1. Under this construction the entire 55 collar-supporter is allowed to swing in a longitudinal plane, so as to accommodate itself to the movement of the horse, whether walking or going at any other gait. So, too, if the horse should throw his head back so as to 60 strike the loop D the supporter will yield and swing in one direction or the other. I wish to point out also that the loop D sets down between the upper ends of the hames G G, so as to be protected thereby and kept 65 out of the way.

In the action of the device the loop D will spring and exert an effort not only to lift the horse-collar, but also to pull it rearwardly enough, so as to permit the free, easy, and 70 unhampered movement of the neck of the horse, whereby his comfort is greatly promoted.

I would have it understood that I do not limit myself to the exact construction herein 75 shown and described, but hold myself at liberty to make such changes and alterations as fairly fall within the spirit and scope of my invention.

Having fully described my invention, what 80 I claim as new, and desire to secure by Letters Patent, is—

1. The combination with a harness-saddle, of a harness-collar, and a yielding collar-supporter pivoted at its rear end to the said saddle, and adapted at its forward end to be connected with the said collar which it 85 yieldingly supports.

2. The combination with a saddle, of a harness-collar, and a yielding collar-supporter pivoted at its rear end to the said saddle and terminating at its forward end in a loop the rear end of which is carried downward and rearward and adapted for the connection with it of the said collar upon which an upward 95 and rearward draft is exerted by the collar-supporter.

3. The combination with the chain-bow of a harness-saddle, of a harness-collar, and a yielding collar-supporter pivoted at its rear 100 end to the saddle, adapted at its forward end to be connected with the collar which it yield-

ingly supports, and formed with a chain-guard extending over the said bow to confine the chain therein.

4. The combination with the chain-bow of 5 a harness-saddle, of a hame-collar, and a yielding collar-supporter pivoted at its rear end to the saddle, provided at its forward end with a loop the end of which is bent downward and rearward and adapted to have the 10 collar attached to it, and formed near its rear

end with an arch-shaped chain-guard extending over the said chain-bow for confining the chain therein.

In testimony whereof I have signed this specification in the presence of two subscribing witnesses.

WILLIAM N. HOUGHTALING.
